NETWORK FOR TOWER LIGHTS

Robert L. Davis, Grand Rapids, Mich., assignor
to Westinghouse Electric & Manufacturing
Company, East Pittsburgh, Pa., a corporation
of Pennsylvania

Application December 12, 1934, Serial No. 757,143

1 Claim. (Cl. 250—33)

My invention relates to transmission by radio and more particularly to a circuit for permitting the mounting of a beacon light or other apparatus in the immediate neighborhood of radio antennae, or on radio towers which either support the antennae, or which in themselves constitute the antennae.

Customary practice in the field of radio transmission calls for the mounting or erection of antennae on high steel towers, the antennae being supported therefrom by insulators. Experience in the use of this construction has shown that the towers, if grounded, distort the field pattern of radiation from the antenna by virtue of the large mass of metal embodied in the tower structure extending up into the region where the electromagnetic and electrostatic field stress about the antenna is very strong. Thus, it has been found necessary, in order to avoid distortion of the field pattern and consequent losses of radio frequency energy due to the absorption of the tower, to insulate the tower from ground at radio frequencies and in some instances, it has been found advantageous to sectionalize the tower itself by inserting insulators between the various sections.

With the development of aviation and air traffic, these tower structures have become a source of danger to airplanes in flight and it, therefore, has become mandatory to provide beacon and aircraft warning lights or other means on these towers to indicate the presence and location of the same to the pilot of an airplane.

To operate such beacons or warning lights on the towers, it becomes necessary to feed power to them from power circuits, which circuits are either directly grounded, or may be considered as being effectively grounded at radio frequencies by reason of the large capacity existing between the power circuits and ground. Thus, the circuit comprising the feed lines running up to the tower to the light, being effectively grounded at radio frequencies, will constitute a source of distortion and a source of loss for the radio frequency energy emitted from the antenna, in the same sense that a grounded supporting tower constituted a distorting medium and a source of loss for the radio frequency energy. However, one cannot dispose of this problem as easily as one would in the case of the tower structure itself, by reason of the fact that one cannot effectively insulate a power circuit from ground at radio frequencies, since such circuits are, as stated above, either grounded directly at various points in the system, or

have such large capacity to ground at radio frequencies due to its length and close proximity to earthed objects that the system might be considered as grounded at radio frequencies.

A similar problem is encountered where the towers themselves constitute the antennae. The power wires running up the towers to the beacon lights or other warning devices must not be permitted to distort the radiated high frequency field nor effectively ground the tower, in spite of the fact that the power system itself may be directly grounded or effectively grounded at radio frequencies.

It is an object of my invention, therefore, to provide a feed circuit for a transmission tower which will be effectively opaque to radio frequencies.

Another object of my invention is to provide means for feeding energy to indicating devices mounted in a high frequency field which feeding means shall be substantially opaque to the flow of high frequency energy therein.

Further objects of my invention will be pointed out in the accompanying description of the same.

As an aid to a clearer understanding of my invention, reference will be made to the accompanying drawing wherein the figure discloses the preferred embodiment of my invention as applied to a warning light mounted on a radio antenna tower.

In this figure, I have illustrated a radio tower 1 fabricated of structural steel and supported above ground by heavy insulators 3 to effectively insulate the tower structure from ground at radio frequencies. At the top of this tower or at some other convenient location thereon is mounted a warning light 5 or other means for indicating the presence and location of the tower to the pilot of an airplane. Energy for use in the operation of this light or indicator is conveyed thereto over a pair of wires 7 which are strung up on the tower and preferably insulated therefrom. The energy may be derived from a source of power supply 9, which may be either a direct-current source or a low frequency alternating-current source, either of which I refer to broadly as a source of power of a frequency of a lower order than that of radio frequency. In the specific example illustrated in the drawing, I have shown the energy as being derived from a conventional 110 volt, 60 cycle supply source both leads to the light being coiled and preferably very tightly coupled. Between the terminals of one of the coils 13, I provide a va-

riable condenser 15, the values of the effective inductance of the two coils 13 and 19 and this shunting condenser 15, plus whatever shunt capacity may exist due to the tower and ground, 5 being such that the circuit is tunable to the radio frequency of transmission from the antenna 17 supported by the tower. A large condenser 18 is connected between the coil 13 and the other coil 19, and by reason of the fact that these 10 coils are closely coupled, a similar tuned circuit will also be effectively included in the power load containing the coil 19.

Thus, in each lead extending to the light, my system effectively provides a parallel resonant 15 circuit tuned to the frequency of transmission, and these tuned circuits will render the power circuit substantially opaque to the flow of radio frequency energy, without impeding the flow of the power energy to the light. Therefore, it will 20 be apparent that the circuit network disclosed by me will insulate the power circuit from ground at the frequency of transmission as effectively as the tower supporting insulators insulate the tower from ground at radio frequency.

25 In the power supply circuit to the light, it is desirable that the same be balanced with respect to ground. Should the power system happen to be grounded on one side, a balanced relationship to ground as regards that portion of the power 30 system which is in the high frequency field, can be obtained by inserting a power transformer 11 in the line and grounding the midpoint of the secondary.

To relieve insulation in the system from effects produced by energy at radio frequency, the 35 power wires 7 to the tower may be bridged by a pair of condensers 20, the midpoint of this condenser bridge being connected to the tower or to the metal conduit enclosing the wires if such 40 is employed.

A circuit similar to that just described will be

employed in connection with the other tower 21 shown in the drawing, although such circuit is not illustrated by reason of the fact that it will involve mere duplication of the circuit already illustrated and described.

5 It will be apparent from the above description that the circuit or system described fulfills the objects of my invention in that the distortion of the field pattern and the radio frequency loss which would otherwise occur due to the presence 10 of the power circuit in the dense radio frequency field around the antenna will be reduced to a minimum and power energy may be safely and conveniently conveyed to an indicating device mounted on the tower, or if desired, on a separate supporting structure located in the proximity of the tower.

15 While I have described the preferred embodiment of my invention in great detail, I do not desire to be limited to the details disclosed and 20 described above, except as may be necessary in view of the prior art and the appended claim.

I claim as my invention:

25 In combination, an antenna tower, an electrical indicating device mounted on said tower, means comprising an electrical circuit for supplying energy of a lower order of frequency than radio frequency to said indicating device, said circuit including a transformer, a coil included 30 in each of the wires of said circuit on the secondary side of said transformer, said coils being closely coupled and connected together at one end of each coil by a condenser of low impedance to radio frequencies, a condenser shunting 35 one of said coils, said coil and shunting condenser being of such value as to constitute a tuned circuit resonant at a desired radio frequency, and means for symmetrically grounding said power circuit at radio frequencies.

40 ROBERT L. DAVIS.
